US00D589922S

(12) **United States Design Patent**
Boyd et al.

(10) **Patent No.:** **US D589,922 S**
(45) **Date of Patent:** **** Apr. 7, 2009**

(54) **HANDSET**

(75) Inventors: **Nicol Boyd**, Brookfield (GB); **Lee Irvine**, Thursley (GB); **Damian Mycroft**, Warwik (GB)

(73) Assignee: **Nokia Corporation**, Espoo (FI)

(**) Term: **14 Years**

(21) Appl. No.: **29/298,923**

(22) Filed: **Dec. 14, 2007**

(30) **Foreign Application Priority Data**

Jun. 14, 2007 (FI) M20070117

(51) **LOC (9) Cl.** **14-03**

(52) **U.S. Cl.** ..... **D14/138 AA**

CLAIM

The ornamental design for a handset, as shown and described.

DESCRIPTION

FIG. 1 is a bottom plan view of a handset showing our new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a front perspective view thereof; and,

FIG. 8 is a rear perspective view thereof.

The broken lines in FIGS. 1, 6, and 7 that show the outermost periphery of non-claimed features represent the boundaries of the claimed design while all other broken lines are directed to environment and are for illustrative purposes only; the broken lines form no part of the claimed design.
